UNITED STATES PATENT OFFICE.

JULIUS H. SCHLAFLY, OF CANTON, OHIO, ASSIGNOR TO THE BERGER MANUFACTURING COMPANY, OF CANTON, OHIO, A CORPORATION OF OHIO.

CONCRETE STRUCTURE.

No. 893,550.

Specification of Letters Patent. Patented July 14, 1908.

Application filed December 18, 1906. Serial No. 343,402.

To all whom it may concern:

Be it known that I, JULIUS H. SCHLAFLY, a citizen of the United States, residing at Canton, in the county of Stark and State of Ohio, have invented certain new and useful Improvements in Concrete Structures; and I do hereby declare that the following is a full, clear, and exact description of the same, reference being had to the accompanying drawing, making a part of this specification, and to the numerals of reference marked thereon, in which—

Figure 1 is a perspective view showing a concrete structure as applied for floor or side walk or other structure showing a part of the concrete broken away. Fig. 2 is a top view showing part of the concrete removed. Fig. 3 is a view on line 2—2, Fig. 2.

The present invention has relation to concrete structure especially designed for floors and side walks and it consists in different parts and combination of parts hereinafter described and particularly pointed out in the claims.

Similar numerals of reference indicate corresponding parts in all the figures of the drawing.

In the accompanying drawing, 1 represents a supporting beam, which is designed to carry the plates or sheets 2, which plates or sheets are substantially of the form shown in the drawing, and as shown they are located side by side so as to produce a continuous surface of a size to correspond with the size of the floor or side walk or structure.

For the purpose of giving the desired amount of rigidity to the plates or sheets 2, said sheets or plates are provided with the angled flanges 3, from which flanges extend the flanges 4.

At the side edges of the bars are located the flanges 5 and 6, which flanges are lapped together as best illustrated in Fig. 3, and for the purpose of assisting in temporarily holding the different plates in proper relative position the flanges 5 are provided with the short upturned flanges 7, which short upturned flanges embrace the angled flanges 3. In some instances and especially in vault and side walk constructions it is desirable to employ blocks of glass or other transparent material such as 8, which blocks of glass or other transparent material are seated in the opening 9 or various plates 2.

For the purpose of giving the structure

additional rigidity the cross-bars 10 are employed, which cross-bars may be located as illustrated in the drawings, that is to say two series of bars spaced from each other and the bars of each series crossed so as to produce increased rigidity in different directions, thereby preventing any vibrations as between the supporting beams. In concrete structures of the class to which this invention pertains it is of importance to form a structure in which there is little or no vibrations, owing to the fact that vibrations have a tendency first to unseat the cement contact, second to crystallize the metal, but by my improved construction this objection and injury to the structure by the vibrations is entirely overcome. In structures where the glass or transparent blocks 8 are employed the cross-bars 10 are located between the rows of the blocks 8 by which arrangement the blocks are bounded upon all sides by the cross-bars, thereby better binding the cement in all directions with reference to glass or transparent blocks 8. In the drawing I have illustrated the cross-bars placed in position simply by having one of the parallel series of bars located under the other parallel series of bars, but I do not desire to be confined to this exact construction and arrangement, owing to the fact that the same object and purpose can be accomplished by the use of coarse netting and in structures where it is not desired to use transparent blocks, the netting may be of any desired construction reference being had to the purpose above pointed out.

It will be understood that the cement is to be placed in position while in a plastic condition after the various plates and cross-bars and netting have been properly assembled and in structures where the transparent blocks are to be employed, said blocks are to be properly connected prior to placing the cement in position. By forming the metal plate 2 as above described the under faces of said plates will present a pleasing appearance and in floor constructions especially the structure will serve the double purpose of ceiling and floor.

Having fully described my invention what I claim as new and desire to secure by Letters Patent, is—

In a concrete structure of the class described, a series of plates having horizontal portions, said horizontal portions provided

with openings, flanges located below the horizontal portions provided with the openings, said flanges provided with horizontal portions located in a plane below the horizontal portions having the openings, said last mentioned horizontal portions provided with upward extended flanges, and a cement body seated upon the horizontal flanges located in different planes, cross-bars located at angles to each other, and between the

openings in the horizontal portions of the plates, substantially as and for the purpose specified.

In testimony that I claim the above, I have hereunto subscribed my name in the presence of two witnesses.

JULIUS H. SCHLAFLY.
